[57] CLAIM

The ornamental design for a biscuit server, as shown and described.

DESCRIPTION

FIG. 1 is a top and side perspective view of a biscuit server showing my new design;
FIG. 2 is a top plan view thereof;
FIG. 3 is a bottom plan view thereof;
FIG. 4 is a side elevation view thereof, the opposite side being identical;
FIG. 5 is an end elevation view thereof, the opposite end being identical;
FIG. 6 is an exploded side elevational view thereof;
FIG. 7 is a vertical cross-section view thereof taken on line 7—7 in FIG. 2; and,
FIG. 8 is a vertical cross-section view thereof taken on line 8—8 in FIG. 2.
FIG. 1 is on a reduced scale relative to the remaining figures.

FIG. 1

FIG. 2

FIG. 3

FIG. 4

FIG. 5

FIG. 6

FIG. 7

FIG. 8
